SHIRT BODY PRESSING MACHINE

Forrest J. Couch, Cincinnati, Ohio, assignor to
 The American Laundry Machinery Company,
 Cincinnati, Ohio, a corporation of Ohio

Application March 25, 1943, Serial No. 480,437

26 Claims. (Cl. 223—57)

This invention relates to shirt body pressing machines, such as are used in commercial laundries for the pressing of men's negligee shirts, with or without attached collars, or other generally similar articles of wearing apparel.

Generally speaking, the invention relates to a machine of the same general type illustrated in certain Rawlinson Patents Nos. 2,126,577, August 9, 1938; 2,195,737, April 2, 1940; and 2,241,373, May 6, 1941, to which reference may be had if desirable or necessary. Machines of this general type include a suitable framework on which is mounted a rotatable turret carrying two or more like upright shirt receiving forms, on each of which a shirt to be ironed may be draped or dressed preparatory to its advance, by turret rotation, into position between two complementary pressing members, which are closed together under pressure upon the form to produce the ironing effect.

One object of the present invention is generally to improve the construction, arrangement and manner of operation of machines of this kind in such manner as to more efficiently and completely accomplish the task for which the machine is designed and by operating and control mechanism which reduces the attention required from the operator and simplifies her task, to the end of producing high quality results at reduced cost per shirt.

More in detail, the invention aims to improve the means and manner of operation of the form and the pressing chests during and at the time of the pressing operation, and to accommodate the machine to shirts of various sizes without liability of distortion of the work.

A further object is to provide an improved machine of this kind including improved means, effective upon or in connection with the rotating turret, for securing appropriate registration or relative position as between the shirt holding form and the press-chests cooperating therewith, and for not only locking or holding the turret in pressing position, but for also releasing it to permit its next advance, when that is desirable.

A further object is to improve the construction of the shirt holding form, not only as to its body portion, but also with respect to its side wings, which are not only adjustable but self-accommodating to various sizes of shirt, and also with respect to the former around which the neckband or collar of the shirt is dressed.

Still another object of the invention is to provide improved means for accelerating or assisting in the drying effect upon the thicker por-

tions of the shirt, such as the side or yoke seams, which ordinarily require more heat and a longer time of pressing than the remaining single thickness portions of the shirt.

5 A further object is to provide an auxiliary drier for the side and yoke seams, which is built in or forms a part of one or both of the heated ironing chests, and which also includes hot air producing and circulating means effective for the supply of heated air to the movable ironing chests and including conduit means for the hot air stream coupled to and uncoupled from the source of supply of hot air by or in accordance with chest movement.

10 15 A further object of the invention is to provide an improved back yoke ironer which is semi-automatic in operation and requires very little attention from the operator, but which assists in ironing the back of the yoke close up to the line where it joins the collar band or collar of the shirt.

Another object of the invention is to provide a machine of this kind including automatic timing or control means to which substantially all 20 25 of the mechanism is subject, so that the machine, during normal operation, repeatedly performs the same cycle of operations over and over again, enabling the operator to give practically her entire time and attention to dressing the shirt properly upon the form and for removing it after the ironing operation is completed.

Finally, another object of the invention is to provide timing means of the character described including an operator-operated disabler by means 30 35 of which the operator, at her will, at the appropriate time, is enabled to interrupt or halt the operation of the timing means and all press operations controlled thereby, so as to stay proceedings, as it were, and enable her to complete 40 the task of dressing the shirt upon the form where special circumstances require more time than the automatic timer makes available for the purpose, such disabling means being of such form that when operated reversely, the interrupted cycle continues exactly where it left off and is completed in the normal manner.

Further objects of the invention are in part obvious and in part will appear more in detail hereinafter.

50 In the drawings, which represent one suitable embodiment of the invention, Fig. 1 is a side elevation, parts of the machine being broken away and in section to expose interior parts; Fig. 2 is a plan view of the machine shown in Fig. 1, some parts being omitted for simplicity of illus-

tration; Fig. 3 is an end elevation, from the left in Fig. 1, of certain portions of the timing and control mechanism, the cover therefor being omitted; Fig. 4 is a sectional plan view thereof on approximately the line 4—4, Fig. 3; Fig. 5 is a fragmental rear end elevation of some of the control parts, looking at the machine in the direction of the arrows 5—5, Fig. 1; Fig. 6 is a diagrammatic view of the electrical control circuits; Fig. 7 is a detail rear elevation of one of the shirt receiving forms or bucks, the view being taken looking at the form from the left in Fig. 8; Fig. 8 is a sectional elevation on the line 8—8, Fig. 7; Fig. 9 is a detail sectional plan view on approximately the line 9—9, in each of Figs. 1 and 7; Fig. 10 is an enlarged fragmental view, in elevation, of a part of the turret frame, a chest carriage and chest; Fig. 11 is a detail sectional plan view on approximately the line 11—11, Fig. 10; Fig. 12 is a detail sectional elevation on the line 12—12, Fig. 11; and Fig. 13 is a diagrammatic view of the control system.

Referring to the machine generally, as shown in Figs. 1 and 2, it comprises a suitable frame including a base 1 at one end supporting an end pillar 2 of hollow cylindrical form, and at its opposite end a standard including a pair of channels 3, the pillar and standard being connected, at the top of the machine, by a cross head or shaft 4. On the pillar 2 is rotatably mounted a turret, marked generally 5, which supports a plurality (two, three or more) of shirt holding forms, two thereof being shown for purposes of illustration, and marked respectively 6, 7. Between the pillar 2 and standard 3 are supported two pressing members, to-wit, a back member 8 and a front member 9, the inner pressing surfaces of which are complementary to those of the form. While one only of said pressing members is required to be movable, both are shown as movable, the front member 9 being actuated by a duplex fluid pressure motor 10, for the closing operation, and the back pressing member 8 by another fluid pressure motor 11, for producing pressure. 12 indicates generally the back yoke ironer, to be described more in detail hereinafter. For assisting in the drying operation the machine is provided with means for supplying a current of hot air, including a fan or blower 13 actuated by an electric motor 14 and communicating by way of conduit 15 with a heat interchanger 16, from which the heated air is delivered for use in drying, as will later appear. The controller and timer for the various machine movements is indicated generally at 17. Within the casing thereof said timer includes an operating electric motor 18, to be referred to hereinafter.

The machine also includes a number of other servo motors, such as a motor 19 for extending and a motor 20 for retracting the wings of the shirt holding forms, a motor 21 for retracting the yoke ironer, a motor 22 for rotating or indexing the turret, and still other smaller servomotors, controlling valves, and other devices to be referred to more in detail hereinafter.

Form and chest operation

When either of the shirt holding forms, by rotation of the turret, reaches the pressing position between the two now separated chests, they are closed together upon it under pressure to effect the ironing operation. One of the chests, such as chest 9, serves as positioning means for the form. Normally the form lies away from

the chest 9, which in operation is moved into contact with the form and then, by its further motion, advances the form to a position just short of engagement with the other chest 8, or it may be in contact but without pressure engagement. In this position the first chest 9 is locked and becomes stationary to form an abutment to receive the pressure applied by the other chest 8.

The moving means for the first chest 9 includes a pair of toggle links, one of which is operated first by a small diameter servomotor piston and then by a larger diameter servomotor piston, the final pressure being applied to the work through leverage actuated by a third large diameter fluid pressure motor. This arrangement reduces air consumption, but secures rapid motion and relatively high pressure.

As illustrated, the frame of turret 5 is provided with tracks 23, Fig. 7, in which travel rolls 24 are attached to the sides of two carriages 25, one supporting each of the forms 6, 7.

Each of the carriages 25, and the form which it supports, is biased to its extreme outer position on the turret by springs 26 surrounding two rods 27, one on either side. One rod 27 is fastened at 28, Fig. 1, to one of the carriages 25 and at its opposite end slides through a guide 29 on the other carriage. Connections of the rods to the carriages are reversed, i. e., each carriage has one rod fastened to it and sliding through a guide 29 on the other carriage. The arrangement equalizes the application of returning effect to both sides of each carriage, preventing binding, and each carriage, when in its outer position, serves as an abutment against which both springs work to return the other carriage.

Chest 9 is suspended by a pair of rods 30 from a hanger 31 which slides along the rod 4. The connection of rods 30 to chest 9 is such as to permit reasonable freedom of action to permit nesting registration or self-accommodation of chest 9 to the form 6 or 7 with which it is to cooperate in the pressing action. At about the mid point of its length, chest 9 is pivotally connected to toggle link 32, pivotally connected at the knuckle 33 to the second toggle link 34, which in this case is a crank or arm mounted to turn with a shaft 35 pivoted in the standard 3.

The hub of toggle link 34 is provided with a gear segment 36 meshing with the teeth of rack 37 formed as a part of the piston rod 38 of the servomotor 10, the teeth of the segment 36 and rack 37 being held in engagement by a backing roller 39. Energization of motor 10 produces downward motion, Fig. 1, of the piston rod 38, moves the toggle links toward straightened position, and advances the chest 9 from the dotted line position toward the full line position, Fig. 1.

Shaft 35 has secured thereto a second arm 40 pivotally connected at its outer end to the piston rod 41 of a suitable air check or snubber 42 pivoted at 43 to standard 3. A strong tension spring or springs 44 opposes the motive effort of the servomotor 10, one end of said spring being connected at 45 to the stationary frame, and its opposite end being attached to the end of a chain or cable 46 passing around a drum 47 fastened to shaft 35, the far end of the chain being attached to a point 48 on the drum.

49, Fig. 2, is a stop on the stationary frame located to be engaged by an ear 50 on the drum 47, to limit opening movement of chest 9.

The arm 51, Fig. 1, serves as an abutment 75 against which the knuckle of the toggle locked

over center bears when pressure is applied by the back chest 8, spring 52 serving to cushion toggle movement as it is closed, and also serving as an initial kicking out device, when the toggle is broken, to start chest opening movement.

The back chest 8 is pivotally mounted on a shaft 53 supported by an arm 54 pivoted at 55 to a bracket or support 56 mounted on pillar 2. The pivotal mounting of chest 8 permits reasonable freedom of movement thereof to secure proper nesting engagement or self-accommodation of chest 8 to the form, when pressure is applied. Spring 51, Fig. 1, under compression between chest 8 and arm 54, maintains the chest substantially in vertical parallelism with the form, when they are separated, but does not affect free self-accommodating adjustment of the chest to the form, as hereinbefore described.

Arm 54 has its upper end forked to embrace the shaft 4 on which slides the piston 58 of servomotor 11, the cylinder of which is properly aligned with and supported by shaft 4 and pillar 2, so as to work with the piston. When fluid pressure is supplied to servomotor 11 it moves to the left in Fig. 1, applying chest 8 to the form under pressure resisted by chest 9, which is now locked in position and serves as a rigid abutment. The actual movement of the chest of course is very slight. Spring 59 serves to return arm 54 and chest 8 and to release the pressure when servomotor 11 is exhausted. Spring 60, Fig. 1, is a simple bumper spring.

The chest closing duplex motor 10 is shown in detail in Fig. 13. As hereinbefore stated, it includes two pistons, differing in size, with parts of the cylinder sized to the respective pistons. The stroke of the first or smaller piston 61 is such as to produce movement of chest 9 sufficient to advance it to a position just short of contact with the form, whereupon the second or larger piston 62 becomes effective to advance the chest and form into their final positions.

In the first open position both pistons are at the upper ends of their respective cylinders 61a, 62a, as shown in broken lines, Fig. 13. To close the chest air is supplied through conduit 63, moving piston 61 downwardly, the post 64 of said piston engaging the piston 62 and moving it and the piston rod 38 downwardly to produce the initial chest closing movement. When the smaller piston 61 reaches the end of its stroke the stem of a valve 65 engages a fixed abutment, opening said valve. Thereupon the pressure fluid flows through or past the valve into the operating chamber of cylinder 62a, causing the second or larger piston 62 to continue its movement and, through piston rod 38, rack 37 and segment 36, to complete closing movement of the toggle links.

The arrangement described retards the advancing motion of chest 9 just as it reaches or is applied to the form, during the closing operation. That is to say, the initial chest movement is produced by small piston 61. As this piston reaches the end of its stroke chest movement is momentarily slowed up to permit it to adjust itself with ease into contact with the form, thereby preventing distortion of the lay of the garment, if contact were produced forcibly or violently. Now the chest 9 and form continue movement under the influence of the larger piston 62, the increased area of which compensates for the extra load in also advancing the form. Therefore constant rate of motion is maintained throughout the closing operation, except at the instant when the chest 9 contacts with the form.

With the two pistons proportioned as described, that part of the operation which requires the greatest amount of movement is accomplished with a small diameter fluid motor. When the duty increases, as when the form begins to move, the piston diameter is increased. Finally, when heavy pressure is required the piston area is again increased by resort to the larger servomotor 11.

10

The shirt holding forms

The shirt holding forms 6, 7 are alike in construction and manner of operation, so that description of one will suffice for both. Each thereof has a body portion which is more or less rectangular when viewed in elevation, as in Fig. 7, and oval in horizontal cross section, as shown in Fig. 9, and which generally simulates the human body. This body portion or frame, marked 66 in Fig. 8, is hollow to provide an interior chamber 67 containing certain operating mechanism and along its side edges is provided with open slots 68 through which are movable horizontally side wings 69 which are flexibly mounted so that when moved outwardly they are self-accommodating to the shape of a shirt and apply uniform stretching action over substantially its entire length.

The hollow body or frame of the form is covered by a rubber sheath 70 enclosed within the usual covering material 71, usually comprising a layer of flannel and a muslin cover cloth, the sheath and cover together forming a yielding padding against which the work is pressed or ironed.

The two forms are identical except as to size. One of them is designed to accommodate a range of shirt sizes, say, up to size 16, and the other is about one inch wider and accommodates a range of sizes from size 16 up. The extra inch in width is indicated in dotted lines, Fig. 7, in the shoulder portions 66a of the padded body, although the wings of the larger form may also be slightly wider, if desired. While the difference in size is sufficiently distinctive, the two forms may also be separately identified as by the color of some permanently exposed part, so that the operator can determine upon which form to dress a small and upon which to dress a large shirt.

Referring to the wings 69, these are alike as to construction and manner of operation. Each has a body portion made of suitable material, such as perforated sheet metal or a wire bent to the external shape of the wing and filled with coarse wire mesh secured around its edges to the wire, the peripheral wire being marked 72 and the wire mesh 73 in Fig. 7. This assembly is then padded with the usual cotton or flannel padding and cover cloth, indicated generally at 74. Each of the wings is removably supported (for purposes of interchange of different sizes, repair or replacement) by a bracket 75 pivotally mounted at 76 for flexible action on one of two like levers 77 pivoted at 78 in the frame or body and provided with an arm 79 engaging a grooved collar 80 on a link 81 pivoted to an arm 82 fast with a shaft 83. In the body are also mounted two arms 84, the upper ends 84a of each having secured thereto one end of a wire spring member 85 looped intermediate its ends around a pin 86 secured in an extension of the upper end of the opposite lever 77, the other end portion 87 of each spring extending downwardly through an opening in an eye 88 attached to one of the brackets 75. Up and down motion of the collar 80 swings the two levers 77

about their pivots 78, but in opposite directions, and since the location and spacing of each arm end 84a to the pin 86 to which it is connected by spring 85 are substantially the same as the relation between the corresponding pivotal connections of arms 84 and 77 to the frame, each wing is moved outwardly and inwardly by a parallel ruler motion, as it were, with yielding support by the vertical spring arms 87, enabling the wings readily to be expanded into a shirt to stretch it to the full extent, but nevertheless self-accommodating to the shape of particular shirts.

Since the wings are of appreciable thickness, and padded, each thereof, when extended, provides solid padded backing of appreciable thickness against which the side portions of the shirt are pressed, as will be readily understood.

The wings are advanced simultaneously to their extended positions by pressure applied by the operator to a handle 89 fixed to the shaft 83. Said shaft also has affixed to it a lever 90 having a lateral extension 91, shown in Figs. 1 and 7, and which, when the form is in pressing position, registers with the head of a plunger 92 of the wing extending servomotor 19, shown in Fig. 13, so that when said servomotor is energized by the supply of fluid pressure thereto the piston 93 thereof moves down and applies the plunger 92 to the extension 91 of lever 90 and completes outward advance of the wings to their final position. Manual operation of the lever 89 produces a gentle stretching action which smoothes out the shirt and removes wrinkles and the final stretch applied by the servomotor 19 occurs just prior to the pressing chest 8 coming into pressure engagement with the form. When motor 19 is deenergized, by evacuation of the pressure therefrom, its piston 93 is retracted by spring 94, Fig. 13.

Lever 90 is used again, later in the cycle, to retract the side wings. When the form carrying the pressed shirt is returned to the dressing position, occupied by the form 6 shown in Fig. 1, another servomotor 20 (Fig. 13) located on one side of the machine frame, Fig. 2, is actuated by the supply of fluid pressure thereto so as to advance its piston rod 95 against the effect of the retracting compression spring 96 into engagement with one arm 97 of a bell crank lever pivoted at 98 in the stationary frame, the other arm 99 of said lever having its end portion lying beneath the same lateral extension 91 of lever 90. Accordingly, energization of servomotor 20 raises lever 90, turns shaft 83 to which it is attached, and through the linkage 81 described retracts the wings. This operation is timed to be performed very soon (a few seconds) after the form has reached the dressing position, the time period being sufficient to permit the operator to remove the shirt from the form so that the side portions of the shirt, in contact with the wings, will not be drawn inwardly with them through the slots in the form through which the wings are retracted.

Preferably, means is provided for releasably holding the wings in any position to which they are adjusted. As illustrated in Fig. 8, the hub 100 of lever 89 is provided with a depending arm 101 having an annularly extending plate portion 102 which lies between two friction shoes 103 pressed toward each other by springs 104 on rods 105. Adjustment of the nuts on said rods produces sufficient friction against the swinging plate 102 to frictionally hold the depending portion of the arm 101, and consequently shaft 83 and the wings connected thereto, in any position to which they may be moved. Preferably each form is provided

with cover cloth fastening means, shown in Figs. 7 and 8 as comprising four rods 106 provided with spurs 107 which grip the tails of the cover cloth. As the rods are revolved in their end supports, by knobs 108, the cover parts gripped by the spurs are wound on the rods and drawn tightly in a downward direction over the form surface. Each rod is provided at one end with a yieldable clutch 109, the teeth of which are yieldingly held together by a spring 110.

Each form is also preferably provided with suitable tail clamp means. The means shown consists of a narrow spring steel member 111 provided with a cross arm 112 at its top. The lower end of the arm is supported by a rod 113 sliding in openings in the form frame and through a square block 114 which rides in a square recess 115 in the frame, as shown in Figs. 7 and 8. The rod is threaded through the block and is sensitive to a compression spring 116, which applies the tail clamp to the form with pressure produced by the spring, adjustment of which is accomplished by turning the rod, as by a screw driver applied to a slot 117 in its end.

Above the wings each form is provided with shirt arm supports, shown as a short rod 118 and a long rod 119 extending through openings 120 in the form and provided at their outer ends with knobs 121. The inner ends of said rods are connected to the long arms of bell crank levers 122 pivoted at 122a, the short arms of said levers being connected to the arms 123 of a yoke secured to a rod 124 slidably in guides 125 on the frame and biased upwardly by an adjustable compression spring 126.

Rod 119 has been provided with extra length for two purposes. First, when the wings are retracted and the shirt is being dressed upon the form, it provides a support for the shirt parts. Secondly, it is on the advance side of the form in the direction of turret rotation. When the form moves into registry between the ironing chests, there is a tendency for the leading sleeve, due to the motion and direction of motion of the turret, to swing backwardly against the side of the form where it might become caught between the chests when they are closed. The greater length of this rod holds the sleeve far enough away to prevent such action.

At its extreme upper end each form is provided with suitable neckband holding mechanism. In the form shown, this includes a block 127 removably secured to the top of the form by nuts 128. The block is shaped to conform to the collar of a shirt, usually of maximum size. To hold the shirt neckband (or collar in the case of a collar attached shirt) in position, I provide an adjustable strip 129, usually made of thin metal, the ends thereof being affixed to a shaft 130 having attached thereto a pair of levers 131 which support a pin 132, through a hole in which slides a rod 133 biased to the left in Fig. 8 by an adjustable compression spring 134. The other end of said rod is pivotally connected to a lever 135 fixed to a shaft 136 having a handle 137 and a stop finger 138 adapted to engage the front face 139 of a support 140. Fig. 8 shows the neckband clamp in release position. When the handle 137 is rotated forwardly (to the right in Fig. 8), the lever 135 is also rotated and by means of the spring 134 causes the levers 131 and shaft 130 to rotate. This rotates the strap 129 into clamping position around and in contact with the shirt collar dressed on the block. 75 Clamping movement is limited by engagement of

the stop finger 138 with the support 140. When the mechanism reaches this stop position the pivot 141 has moved clockwise in Fig. 8 over center to the other side of a line between pivots 132, 136, and the action of the same spring 134 holds the strap releasably against the block, the operation being after the manner of over-center snap mechanism. Levers 131 support between them a roller 142, which lies above a lateral extension 143 of the vertical rod 124 before referred to. Consequently when lever 137 is operated to move the clamping strap 129 into clamping position, the same operation depresses rod 124 and moves the rods 119 outwardly into the sleeves to support them more or less in horizontal position, as will be readily understood.

Turret operating mechanism

The turret 5 is rotated or indexed periodically, at one point in each cycle of operations, by a fluid pressure servomotor 22 (see Figs. 2 and 13), the piston rod 145 of which supports a block 146 which is adapted to swing freely upon the rod and is fixed against longitudinal movement thereon by collars 147 and 148. The block has an upwardly extending lug 149 which is adapted, when the cylinder is evacuated, to lie back of the extension 150 of an arm 151 attached to the turret frame. There is one such arm for each shirt holding form carried by the turret, two in the present instance. Block 146 is weighted at its lower end 152 so that while it is free to swing it is biased to a normal position with the lug 149 extending upwardly. The outer end of the piston rod is supported and guided in an opening in a bracket 153, in which it is free to slide.

When fluid pressure is supplied to the servomotor cylinder a kicking impact is applied by the block 146 to the arm 151, effective to advance the turret frame. When the frame, by free motion, has rotated 180°, in the present instance, it is stopped and the other like arm, on the other side of the turret frame, assumes the position previously occupied by the first arm. The cylinder 22 is now evacuated and a spring 154 connected between collar 148 and a suitable point on the machine base returns the piston rod and block. As the block, during its return movement, reaches the next arm 151 it engages the inclined face of the extension 150 thereof and is cammed out of the way, turning on rod 145, so that the block is thereby permitted to pass the extension 150. When it has passed, the weighted base 152 swings the block back to normal upright position for engagement with the next arm 151 for the next turret rotation.

Brake means is provided to absorb most of the inertia of the freely moving carriage as it approaches the new position. This comprises a plate 155 attached to the base of the machine frame, as shown in Fig. 1, so as to lie beneath the path of movement of a brake shoe 156 (Figs. 1, 7 and 10). Referring to Fig. 7, the brake shoe 156 is pivotally supported on an arm 157 which in turn is pivoted at 158 on a bracket 159, the other end of said arm having an opening to receive a rod 160 biased downwardly by an adjustable compression spring 161. Adjustment of this spring is made initially to cause the brake shoe to press on the plate 155, when it reaches it, with sufficient force to slow down the turret frame, as it approaches registering position, to a speed which will permit it to move definitely but easily into the turret locking mechanism now to be described.

The turret locking and registering means is best shown in Figs. 1, 10, 11 and 12. It includes a pair of blocks 162, 163, both of which are mounted for free rotation on a shaft 164 supported by two side angles of the main frame 1. These blocks are biased to a vertical position with their sides contacting an abutment 165 by springs 166, 167 respectively. As shown in Fig. 12, the normal position of these blocks, lengthwise of shaft 164, is determined by the springs 168, 169. Spring 169 serves as a spacer and also as a cushion. Spring 168 serves as a cushion and also as a strong biasing means to return the block 163, longitudinally of the shaft, to a normal position, as will appear later.

Block 162 has a laterally extending branch 170, the face 171 of which is cut off or inclined to the path of rotational movement of lugs 172, one for each shirt holding form, attached to and depending from the form holding carriages 25.

In the operation of this device, as the turret frame approaches registering position, one of the lugs 172 engages the angular face 171 of block 162, cams it to the left, Fig. 11, out of the way, 25 and thereby passes block 162 and engages broadside against the block 163, now in normal vertical position in contact with abutment 165. The inertia of the moving frame is absorbed not only at the friction shoe 156, but partially by the 30 spring 168, which is compressed. Sufficient movement of lug 172 is permitted, however, so that it entirely passes block 162, which then returns to its normal vertical position against abutment 165 by the force of spring 166. The energy 35 stored in spring 168 by the moving turret frame now becomes effective to return the frame to a position where the lug 172 engages broadside against the transverse backface of block 162, in its full line position, Fig. 11. In this position the 40 turret frame, and the shirt holding forms thereon, are in properly registered position with relation to the pressing chests, for pressing operation on one form and unloading and loading of the other form.

When the form moving carriage at the pressing station is moved to the right in Fig. 1, or toward the turret center, the lug 172 moves to the right in Fig. 11 out of the path of rotational cooperation with blocks 162 and 163. Spring 168 45 then becomes further effective to move the block 163 into abutting relation with spacer spring 169, so that it is separated from block 162 by a distance less than the thickness of lug 172. Consequently block 163 now lies in the path of the return movement of the lug 172 when the carriage returns to the left in Fig. 1. Lug 172 therefore 50 engages block 163 and rotates it to the position shown in Fig. 11, whereupon block 163 is no longer effective as a locking means and the turret frame is free to be advanced by turning movement for the next operation.

The shirt pressing chests

As shown in Fig. 9, each of the two pressing 55 chests is hollow, the chamber or chambers 173 therein communicating by any suitable means, such as flexible conduits 174, with a source of heating steam. Their inner pressing surfaces are of polished metal and are shaped complementary to the external surface of the forms, as 60 shown in Fig. 9, flat wings 175 of the chests engaging the flat surface of the adjustable padded form wings. Accordingly, heat and pressure are applied over the entire area of the shirt to dry, 65 smooth and iron the same. Referring to Fig. 1,

it will be noted that chests 8 and 9 are recessed just above wings 69 to accommodate shoulder portions 66a of varying width.

Additionally, I provide auxiliary heating means for the side seams of the shirt and around the seam connecting the collar and yoke, where these parts do not come into intimate or direct contact with the hot chests.

The heating means for this purpose includes a chamber 176 on the front chest 9 formed between the outer wall 177 of the chest body and a thin metal shield or jacket 178 attached thereto and provided along its vertical side edges with extensions 179 curved at their outer ends to form lips 180 lying close to the outer vertical edges of the wings 175 to form a narrow vertically extending mouth of slot-like form closely adjacent to and immediately outside of the outer edges of the padded form wings 69. By supplying heated air to the chamber 176 it is directed by the lips 180 through the slot-like mouths 181 upon the side seams of the shirt to accelerate the drying thereof and complete the drying task in time with the thinner body portion of the shirt.

The hot air supply is produced by the fan 13 operated by electric motor 14, Figs. 1 and 2, the air stream being carried by conduit 15 to and through the heater 16, which is provided with heating steam coils 182.

Referring now to Fig. 10, the upper end of the chamber of the heater is normally closed by a damper 183 pivoted at 184. When the form carriage 25 is at its outermost position on the turret frame, as shown in full lines, Fig. 10, said damper is held closed by a spring 185. When the carriage 25 is advanced into pressing position, indicated by the dotted lines at the right in Fig. 10, a flange 186 at the lower end of a hollow conduit 187 engages lever 188 and turns the damper to open position. At the same time a collar 189, normally biased upwardly by springs 190, is depressed so as to maintain a tight seal between said collar and the flange 186. Heated air therefore is admitted to the hollow conduit 187 which communicates with an outlet passage 191 in a nose 192, Fig. 8. The open end of the nose 192, as shown in Fig. 10, lies in such position that when the chest 9 is advanced to engage the form 6 or 7, a yielding collar 193, similar in construction and arrangement to the collar 189 and mounted on a hollow conduit member 194, engages the end of said nose and produces a tight seal between the two parts, establishing communication from passage 191 and through the channel 195 and opening 196 to the hot air chamber 176 of the chest.

Accordingly, assuming the motor 14 is in operation, so long as the form lies in pressing position and is subject to pressure between the pressing chests, a stream of hot air is conducted and directed from the heater 16 to the chamber 176 and is distributed therefrom and applied to the side shirt seams for drying the same, as described. When pressure is relieved and the chests and form return to normal position, the air flow is cut off by the damper 183.

Hot air for heating the neckband seam is supplied through each of the forms, as shown in Figs. 7 and 8. As there indicated, hot air supplied to the passage 187 within hollow conduit 187 is directed by a channel 198 to the chamber within the hollow form from which it flows by way of pipes 199 to a channel 200 in the neckband receiving block, said channel 200 communicating with a series of small openings 201, Fig. 7, which

terminate at their outer ends in an annular air distributing groove 202 around the collar block and which registers with the seam between the collar or neckband and yoke when the shirt is in properly dressed position. Therefore, during the pressing operation heated air is being constantly applied to this seam.

Yoke ironer

10 The machine is preferably also provided with means for ironing parts of the back yoke around the collar. This is best shown in Figs. 1 and 2. It comprises a hollow ironing shoe 203 shaped at its forward edge to fit around the collar, as shown in Fig. 2. The chamber in said shoe is supplied with heating steam, as by flexible pipe connections indicated conventionally at 204.

This shoe is supported movably on the stationary frame, and more particularly on pillar 2. It is rigidly mounted upon a pair of arms 205 connected by links 206 to a bracket 207 attached to pillar 2. The lower ends of the two front links 206 are fixed to a shaft 208 to which is attached a lever 209 pivotally connected to the rod 210 of a fluid pressure servomotor 21. The yoke ironer is normally biased to operating or ironing position by a spring or springs 211, being returned to the inoperative full line position, Fig. 1, by energization of servomotor 21, at a time and in a manner to be described later.

25 Each of the form supporting carriages 25 is provided with a snubber in the form of a piston 212, Fig. 8, which works in a cylinder 213 formed in the carriage. The piston rod is attached to the turret frame and the cylinder moves freely on the piston when the carriage is advanced to pressing position (movement toward the left in Fig. 8), air being freely drawn in to the piston chamber through the relief valve 214. However, when the carriage returns to its outer position, the cylinder is evacuated through an adjustable restricted orifice 215, with any desired snubbing action.

ress of the automatic control cycle under special circumstances, as will appear.

As shown in Fig. 6, the electrical system is simple. It includes the two electric motors, motor 14 for the fan 13 and motor 18 for the automatic timer, connected in parallel by way of switch 218 with the leads L₁, L₂, L₃. Switch 218, as shown in Fig. 1, is located at the front end of the machine just above the yoke ironer, in convenient position for manipulation by the operator. The circuit to motor 18 includes a disabling switch 219 to be referred to later.

The fluid pressure system, for operation and control purposes, includes a main fluid pressure conduit 220 communicating with a suitable source of fluid pressure, not shown, which supplies pressure fluid by pipe 221 to a combination supply and exhaust valve 222, by conduit 223, to a normally closed valve 224 and by way of a pressure regulator 225 to a combined supply and exhaust valve 226. A combination valve 222 is located at the rear end of the machine near the base, as shown in Figs. 1 and 5. It is actuated by a pivoted lever 227 which in turn is actuated by a blocking lever 228. When the press is operating automatically, this valve is maintained in open position by the block, with the parts in the position shown in Fig. 13. Block 228 is connected by a link 229 with a lever 230 on a shaft 231 which extends to the front end of the machine, where it is provided with a foot treadle 232. This valve 222, therefore, may be manually closed for a purpose to be later described. It controls the supply of fluid pressure to a combination valve 233.

Valve 233 is actuated by a lever 234 operated by cam 235 on shaft 35, which supports and operates the toggle operating gear segment 36, Fig. 1. This valve is opened by the cam to pass fluid pressure when the toggle is in the chest open position, shown in dotted lines at the left, Fig. 1. Valve 233 controls the supply of fluid pressure by way of conduits 236 and 237 to the turret turning fluid pressure servomotor 22, and by way of conduit 238 to a servomotor 239. An adjustable needle valve 240 in conduit 237 regulates the flow of air to motor 22.

The operation of the turret turning motor has already been described.

Servomotor 239 operates in connection with the servomotor 21 of the yoke ironing device. Its piston operates a pivoted blocking lever 241 which in normal position, shown in Fig. 13, serves to hold the actuating lever 242 of the valve 226 in the valve closing position shown. These parts 239, 241, 242 and 226 are located at the forward end of the machine, as shown in Fig. 1. The supporting shaft 243 for the blocking lever 241 extends to the front of the machine where it is provided with a foot treadle 244 by which it may be rotated. Lever 241 is moved to its blocking position to close valve 226, by depression of treadle 244, and is automatically retracted to release lever 242 and permit self-opening of valve 226, by energization of the servomotor 239.

The valve 226 is connected by conduit 245 with the servomotor 21 for retracting the yoke ironer. In the conduit 245 is a check valve 246 seating toward valve 226 and permitting the flow of air only in a direction toward the servomotor. This check valve is by-passed by a conduit 247 including an adjustable needle valve 248, which controls the evacuation of servomotor 21 and thereby snubs the motion of the yoke ironing

member, by the effect of springs 211, into ironing position.

Valve 224 is mounted on the rigid frame of the machine, as shown in Fig. 1, and is actuated to open it by a roller 249 mounted on a support 250 on the rotatable turret frame.

This valve is opened as the turret frame reaches a position in which the shirt form registers with the pressing chests. It controls the flow of supply of pressure fluid by way of conduits 251 and 252 to a combination valve 253, by conduit 254 with a combination valve 255, and by a continuation of conduit 251 with a combination valve 256.

15 The valve 253 is located on the rear standard 3 of the machine frame and is operated through lever 257 by the cam 235. This valve is open when the toggle links 32, 34 are in chest closed position. It controls the supply of pressure fluid by way of conduits 258 and 259 to the wing extending servomotor 19, and by way of conduit 260, an adjustable needle valve 261 and a check valve 262, with a combination valve 263. The valve 263 in turn controls the supply of fluid pressure by way of a conduit 264 to the heavy pressure servomotor 11. This valve, together with a servomotor 265 for operating it, is mounted near the upper end of the pillar 2, near the pressure motor, as shown diagrammatically in Fig. 1.

20 The combination valve 255 is located at the rear of the machine in the housing 266 of the automatic timer 17 (see Fig. 1) and is shown in detail in connection with the timing mechanism 35 in Figs. 3 and 4.

25 It is operated by a lever 267 which is operated by a cam 268 forming a part of the timer to be later described. This valve 255 controls the supply of fluid pressure by way of conduit 269 and conduit 63 to the chest closing motor 10. An extension of conduit 269 also supplies fluid pressure to the servomotor 265 before referred to.

30 When valve 255 closes, pressure in the cylinder 10 is evacuated through conduit 63 and also by conduit 270 and its check valve 271. Servomotor 265 is also exhausted to pipe 269. The exhaust outlet of valve 255 is provided with an adjustable orifice 272 which permits the rate of exhaust to be controlled to snub the opening movement 35 of the piston of motor 10 and the chest 9 which it operates. When the piston 62 engages post 64 the piston 61 of course also returns, valve 65 closing.

35 Combination valve 256 is actuated by a lever 273 operated by a cam 274 of the timer mechanism. This valve 256 controls the supply of fluid pressure to the wing retracting motor 20 by way of conduit 275. The physical location of valve 256 is illustrated in Fig. 3.

Timing mechanism

The timing mechanism 17 is enclosed within the casing 266, Fig. 1. It includes the cams 268, 274 before referred to, and their operating mechanism. These cams are adjustable relative to each other over a limited range, as shown in Figs. 3 and 13, by means of the slot 276 and stud 277. They are definitely positioned relative to each other for any given time cycle and are capable 40 of change within that range found to be necessary in the operation of a machine of this kind. Change of the pressing time is effected by adjustment of cam 268 relative to the plate 278, by means of slot 279 and stud 280, the adjustment varying the relative circumferential extent of

the full height lobe of cam 268, 278 with reference to its recess.

Shaft 281, to which plate 278 is fixed, is connected by a train of gears marked generally 282, Fig. 4, to the shaft 283 of a worm wheel 284 driven by a worm 285, the shaft 286 of which has affixed to its outer end a friction disk 287 driven by a friction wheel 288 on the shaft of electric motor 18. The motor, motor shaft and friction wheel 288 are adjustably mounted upon a stationary base 289, an adjusting screw having a head 290, being provided to vary the position of engagement between wheel 288 and disk 287, so as to vary the speed of the timer shaft and cams, motor 18 being a constant speed motor. The direction of rotation of the cams is clockwise as viewed in Fig. 3.

Timer disabling mechanism

As previously described, the cam 274 actuates the valve 256 through lever 273; and cam 268, 278 actuates the valve 255 through lever 267. This lever is mounted freely on a shaft 291, being biased to maintain contact with the cam, by a tension spring 292. Associated with lever 267, and also freely mounted upon the shaft, is another lever 293, interconnected with lever 267 by a lateral branch 294 on lever 293 adapted to engage the depending arm of lever 267. The hub of lever 293 is provided with a boss 295 having an arm 296 supporting an adjustable weight 297 just heavy enough to counterbalance the lever 293. One arm of lever 293 is connected to a link 298 between collar nuts 299 and a compression spring 300 thereon, the link 298 being connected to block 228, as shown in Figs. 5 and 13, and the depending arm of lever 293 being connected by link 301 to the electric switch 219, shown in Figs. 3 and 6.

Fig. 3 illustrates the parts in their positions when operating automatically during a cycle. It will be noted that there is clearance between the arm of lever 293 and collar 299 and the end of spring 300. In this position spring 300 is slightly compressed and serves as a motion relief to protect the switch 219 when the rod 298 is elevated. In the switch casing is located a switch 302, to be referred to later.

The purpose of the mechanism just described is to interrupt automatic operation of the machine during a cycle. Such an interruption may be necessary or desirable in order to give the operator, at her option, more time for any purpose, such as to dress a shirt on the form at the dressing position. Ordinarily the time allotted to her by the automatic cycle is sufficient, but emergencies may arise, such as a shirt of unusual style or design, or for other reasons where additional time is required or it may be desired temporarily to shut down the machine.

In such event the operator depresses the foot treadle 232 to rotate shaft 231 in a clockwise direction, Fig. 5. This elevates rod 229, rotates block 228 clockwise, permitting valve 222 to close. However, this is only a partial movement of the treadle permitted by the clearance between the collar and the branch of lever 293. When these parts engage, treadle motion is stopped, because the roller on lever 267 is riding on the full height lobe of cam 268.

Downward movement of rod 298 has relieved the compression of spring 300. Under these conditions the compressed spring 302 in the switch housing becomes effective to rotate lever 293 counterclockwise as soon as such motion is per-

mitted by the cam 268. This happens when the low point in the cam reaches the lever 267. The switch 219 then opens, and the lever 267, rotating counterclockwise into the low level of the cam, closes valve 255 to exhaust.

By referring to Fig. 13, it will be observed that when valve 222 is closed, the supply of fluid pressure to the turret turning motor 22 is blocked.

When the operator has completed the dressing operation on the form at the dressing station, she returns treadle 232 to its normal position and reestablishes the automatic operation or continuance of the cycle.

It will be observed that the timer disabling mechanism described is of such construction and arrangement as to make it impossible to complete interruption of the automatically controlled cycle during the actual pressing portion of the cycle. That is to say, when the operator depresses the

20 treadle 232, the first effect is to close valve 222 and block the supply of fluid pressure to the turret indexing motor 22, but operating effect upon switch 219 is delayed pending rotation of cam 268 until the roller on lever 267 can enter the low part thereof. When this occurs valve 255 is opened to exhaust and the press closing motor 10 is evacuated, with a certainty that neither the pressing mechanism nor the timing motor stop until the pressing operation is completed and the chests are in open position.

Complete operation

In describing a typical cycle of operations of the machine, it will be assumed that one pressing operation is in process at the pressing station, and that a finished shirt has just been removed from the form now in the dressing position at the right in Fig. 1. This form is numbered 6. At this particular instant, it will also be assumed that a part of the pressing cycle has been completed, as shown by the location of the cams 268, 278, with reference to lever 267, Fig. 13. Cam 274, rotating clockwise in Fig. 13, has passed the roller on lever 273, so that the wing retracting motor 40 20 has been actuated to retract the wings on the form 6.

The operator now dresses a shirt on form 6 by applying it to the form from the back and above, threading the longer sleeve rod 119 through the right sleeve. She then draws the shirt across the back of the form and over its left shoulder portion. The collar or neckband is then dressed around the block in an upstanding position. The operator then pulls forwardly 50 on handle 137, applying the clamping band 129 and at the same time depressing rod 124 to extend the two sleeve rods 119, 120. She then depresses the treadle 244 which rotates the block 241 to a blocking position, which closes the valve 226. This evacuates cylinder 21 of the yoke ironing mechanism, which exhausts under control of the needle valve 248 and permits the springs 211 to ease the yoke ironing shoe 203 into position against the portion of the shirt yoke around the collar. She then pulls downwardly on the button-hole strips and secures the right and left front tails of the shirt under the respective branches 65 112 of the tail clamp 111. This action completes the dressing of the front of the shirt upon the form.

Thereupon the operator depresses lever 89 to initially extend laterally the two side wings 69. She then pulls downwardly upon the back tail of the shirt and smoothes out its back.

75 Since the electric switches 218 and 219 are

closed, the timing mechanism, including shaft 281 and its cams, is rotating continuously and by this time the point 303 (Fig. 13) of cam 268 has reached the roller on lever 267, and as the roller enters the recess of the cam, valve 255 closes, causing evacuation of the fluid motors 11 and 18. Pressure is relieved, shaft 35 rotates, and the toggle links 32, 34 open, drawing the chest 9 away from the form. Springs 26 are now effective to return the form 7 to its outermost normal position on the turret frame. Lug 172 engages the block 163, moving it out of the way, and the turret is free to be rotated.

When the toggle links have completed their opening movement, the cam 235 moves out of contact with lever 257, causing valve 253 to close, exhausting the wing extending servomotor, and the same cam 235 has moved into contact with lever 234, opening valve 233 to supply fluid pressure to the servomotor 238 and also to the turret turning motor 22.

Energization of servomotor 238 moves the block 241 out of the way, causing valve 226 to open, which energizes servomotor 21, causing the yoke ironing shoe 203 to be retracted to its inoperative position.

At practically the same time, or a moment thereafter, the piston of servomotor 22 begins to move and cause turret rotation. Since the response of the motor 21, when valve 226 is opened, is more rapid than the response of motor 22, the complete removal of the yoke ironing shoe, before turret rotation begins, is assured.

When the piston of motor 22 has completed its stroke and accomplished, in the form illustrated, 180° of rotation of the turret, the form 6, on which a fresh shirt has been dressed, reaches registering position between the ironing chests. Motion of the turret is retarded or braked by the plate 155 and brake shoe 156, and the lug 172 cams the block 170 out of the way and engages block 163 broadside, whereupon turret motion is stopped and the turret is locked in this position, as previously described.

In this position a roller 249 at the end of the turret actuates valve 224 to open it, thus supplying fluid pressure to valves 253, 255 and 256. Shortly after registration is completed, the high point 303 of cam 268 actuates lever 267 to open valve 255, which permits passage of pressure fluid to the motors 10 and 265. Motor 10 moves chest 9 against the form and advances the form into position for pressure engagement by the chest 8. In this position the toggle links 32, 34 are locked over center.

Energization of servomotor 265 opens valve 263, supplying fluid pressure to the servomotor 11, which applies chest 8 with heavy pressure to the form.

When the toggle links reach straightened position the cam 235 actuates the lever 257 to open valve 253. This supplies pressure fluid to the wing extension motor 19, and since the same fluid line supplies pressure to valve 263, the energization of the wing extending motor takes place just prior to the energization of the final pressure motor 11. When motor 19 is energized, its plunger 92 engages the lever 90 to cause a final stretching action of the wings. This final extension takes place just before the final pressure chest 8 moves into pressure contact.

When the form reaches pressure position by inward motion toward the center of the turret, the flange 186 of its conduit 187 registers with and depresses the collar 189 at the mouth of the 75

heating chamber, and the damper lever 188 has been actuated to open the damper and supply heated air both to the neckband block, through conduits 199, and by way of conduit 195 and chamber 176 to the edges of the wing members and the side seams of the shirt there exposed.

The form 7 is now in the dressing position and the operator is removing the finished shirt therefrom. About the time she completes this 10 operation the cam 274 engages lever 273 and opens valve 256 which supplies fluid pressure to the wing retracting motor 28, which acts through the bell crank lever 97, 98, to raise lever 99 and cause retraction of the wings. This operation is timed so that the operator has plenty of opportunity to remove the shirt before this operation takes place, thus preventing drawing of the finished shirt into the wing slots and causing them to become mussed. The operator then proceeds with the dressing of another shirt on form 7 and the cycle is repeated, as before.

Large and small shirts are distributed between the large and small forms, as will be readily understood.

25 If the operator anticipates requirement for an unusually long pressing period, she applies her foot to the treadle 232, which first cuts off the supply of fluid pressure to the turret turning motor and, when the immediate pressing operation 30 has been completed, opens the switch 219 and shuts down the timer motor. When the desired time interval has expired the operator again actuates treadle 232 to return it to its normal position, which re-establishes operation of the automatic cycle, but not until the hot chests have been removed from the form at the pressing station.

The details for steam supply to the various heating units have not been shown where they 40 would be confusing. Suffice it to say that the supply pipes are out of the path of travel of forms 6 and 7, located overhead, and connected by flexible hose with the upper connections 174 and 204 for the chests 8 and 9 and for shoe 203 respectively. The lower or drain connections for chest 8 and shoe 203 are led away through pillar 2. The drain connection for chest 9 can be led away without difficulty.

50 What I claim is:

1. Apparatus of the character described, comprising a shirt form mounted in erect position and movable horizontally, opposed heated chests cooperating therewith, motor means for advancing one chest into pressing relation with the form, a second motor means for advancing said chest and the form into pressing relation with the second chest, and a third motor means for applying the second chest to the form with heavy pressure for producing an ironing effect.

2. Apparatus of the character described in claim 1, in which the several motor means are each of piston and cylinder servomotor form and the pistons thereof are of increased diameter in 65 the order named.

3. Apparatus of the character described, comprising a padded shirt holding form, two opposed cooperating ironing members adapted for application to opposite faces of said form, one thereof being movable toward and from the other, said form and ironing members being so shaped that the side seams of the shirt lie outwardly beyond the pressing area and are exposed during the pressing operation, and means carried by the movable ironing member for directing a moving

stream of drying air upon the exposed side seam portions of the shirt.

4. Apparatus of the character described, comprising a padded shirt receiving form, two opposed relatively movable ironing chests adapted for application to said form, said form and chests being so shaped that the side seams of the shirt are exposed during the pressing operation, one of said chests being provided with a channel having an elongated mouth lying adjacent a side seam during the pressing operation, and means for supplying drying air to said channel.

5. Apparatus of the character described, comprising a padded shirt receiving form, two opposed relatively movable ironing chests adapted for application to said form, said form and chests being so shaped that the side seams of the shirt are exposed during the pressing operation, one of said chests being movably mounted and provided with a chamber having an elongated mouth the lip of which lies adjacent a side seam during the pressing operation, and means for supplying drying air to said chamber.

6. Apparatus of the character described, comprising a frame, cooperating opposed pressing members one of which is movably mounted upon said frame, a movable support carrying a plurality of upright shirt receiving form members adapted to be selectively moved into pressing position between said pressing members, said movable pressing member being provided with an air supply chamber provided with an inlet and also having an outlet lying beyond the pressing area and thereby being located to direct air upon a portion of the shirt which is exposed when the pressing members are in pressing position, and an air supply conduit on the form member having a discharge opening adapted to register with the air inlet on the movable pressing member and arranged to supply drying air to said chamber only when the movable pressing member is applied to the shirt holding form.

7. Apparatus of the character described, comprising a frame, cooperating opposed pressing members one of which is movably mounted upon said frame, a movable support carrying a plurality of upright shirt receiving forms adapted to be selectively moved into and out of pressing position between said pressing members, each form having a neckband receiving block provided with an air distributing channel extending along the neckband seam of the shirt, the form being provided with conduit means having an inlet and communicating with said channel, and air supply means on the frame having a discharge opening with which said inlet registers when the pressing members are closed upon a form for supplying drying air to said conduit means.

8. Apparatus of the character described, comprising a frame, cooperating opposed pressing members one of which is movably mounted upon said frame, a movable support carrying a plurality of upright shirt receiving forms adapted to be selectively moved into pressing position between said pressing members, each form having a neckband receiving block provided with an air distributing channel extending along the neckband seam of the shirt, said movable pressing member being provided with a chamber having an outlet lying adjacent a portion of the shirt when in pressing position, a source of drying air on the frame, and means arranged upon relative approach pressing movement between the pressing members for establishing communica-

tion from said source to said chamber and from said chamber to said channel.

9. Apparatus of the character described, comprising a frame, a turret rotatable therein and carrying a plurality of shirt forms each movable radially on the turret, movable ironing means on the frame for cooperation with the form at a pressing station, means for rotating the turret to bring a form into registration with the ironing means, turret locking means, and means for releasing the locking means operated by movement of the form on the turret.

10. Apparatus of the character described, comprising a frame, a turret rotatable therein and carrying a plurality of shirt forms each movable radially on the turret, movable ironing means on the frame for cooperation with the form at a pressing station, means for rotating the turret to bring a form into registration with the ironing means, means for stopping the turret and for locking it when the form is registered with the ironing means, and means whereby application of the ironing means to the form releases the turret locking means.

11. Apparatus of the character described, comprising a frame, ironing means movably mounted thereon, a turret carrying a plurality of shirt holding forms and adapted by its rotation to move them from a dressing station to ironing position, and ironing means movably mounted on the frame at the dressing station and adapted for cooperation with any one of said forms when at said station for ironing a portion of the shirt on such form.

12. Apparatus of the character described, comprising a frame, ironing means movably mounted thereon, a turret carrying a plurality of shirt holding forms and adapted by its rotation to move them from a dressing station to ironing position, and a yoke ironer movably mounted upon the frame at the dressing station and cooperating with any one of said forms when at said station for ironing the yoke portion of the shirt on such form.

13. Apparatus of the character described, comprising a frame, ironing means movably mounted thereon, a turret carrying a plurality of shirt holding forms and adapted by its rotation to move them from a dressing station to ironing position, a yoke ironer movably mounted upon the frame at the dressing station, and operator-operated control means for causing application of the yoke ironer at the will of the operator to the shirt on any form when at said dressing station.

14. Apparatus of the character described, comprising a frame, ironing means movably mounted thereon, a turret carrying a plurality of shirt holding forms and adapted by its rotation to move them from a dressing station to ironing position, a yoke ironer movably mounted upon the frame at the dressing station, operator-operated control means for causing application of the yoke ironer at the will of the operator to the shirt on any form when at said station, and automatic means for retracting the yoke ironer.

15. Apparatus of the character described, comprising a frame, movable ironing means supported by the frame at an ironing station, a rotatable turret carrying a plurality of movable shirt holding forms and adapted by its rotation to move them from a dressing station to the ironing station, operating means therefor, means for applying the ironing means to the form, automatic

control means for causing a cycle of operations of the turret rotating means and movable ironing means, including advance and recession of said ironing means, and disabling means operable by and at the will of the operator for temporarily stopping operation of said control means.

16. Apparatus of the character described, comprising a frame, movable ironing means supported by the frame at an ironing station, a rotatable turret carrying a plurality of movable shirt holding forms and adapted by its rotation to move them from a dressing station to the ironing station, operating means therefor, means for applying the ironing means to the form, automatic control means for causing a cycle of operations of the turret rotating means and movable ironing means, including advance and recession of said ironing means, and disabling means operable by and at the will of the operator for temporarily stopping operation of said control means after the lapse of a delay period terminated by said control means.

17. Apparatus of the character described, comprising a frame having spaced dressing and ironing stations, movable ironing means supported by the frame at the ironing station, a rotatable turret carrying a plurality of shirt holding forms and adapted by its rotation to move said forms from the dressing station to the ironing station, operating means therefor, means at the ironing station for applying said ironing means to the form, a yoke ironer movably mounted on the frame at the dressing station, and automatic control means for sequentially causing pressure relieving operation of the yoke ironer with respect to such form, turret rotating operation of the turret operating means, and pressure applying operation of the movable ironing means with respect to the same form.

18. Apparatus of the character described, comprising a frame having spaced dressing and ironing stations, movable ironing means supported by the frame at the ironing station, a rotatable turret carrying a plurality of shirt holding forms and adapted by its rotation to move said forms from the dressing station to the ironing station, operating means therefor, means at the ironing station for applying said ironing means to the form, a yoke ironer movably mounted on the frame at the dressing station, operator operated means for causing application of said yoke ironer to a form at the dressing station, and automatic control means for sequentially causing pressure relieving operation of the yoke ironer with respect to such form, turret rotating operation of the turret operating means, and pressure applying operation of the movable ironing means with respect to the same form.

19. Apparatus of the character described, comprising a frame, movable ironing means supported by the frame at an ironing station, a rotatable turret carrying a plurality of movable shirt holding forms and adapted by its rotation to move them from a dressing station to the ironing station, operating means therefor, means for applying the ironing means to the form, a yoke ironer mounted on the frame at the dressing station, operator-operated means for causing application of the yoke ironer to the form, automatic control means for causing a cycle of operations including release of the yoke ironer from the form, rotation of the turret, and application of the ironing means to the form, and disabling means operable by and at the will of the operator for

temporarily stopping operation of said control means.

20. Apparatus of the character described, comprising a frame, movable ironing means supported by the frame at an ironing station, a rotatable turret carrying a plurality of movable shirt holding forms and adapted by its rotation to move them from a dressing station to the ironing station, operating means therefor, means for applying the ironing means to the form, a yoke ironer mounted on the frame at the dressing station, operator-operated means for causing application of the yoke ironer to the form, automatic control means for causing a cycle of operations of the yoke ironer, rotation of the turret and application of the ironing means to the form, operator-operated means for actuating said control means to interrupt said cycle of operations, and means for delaying such interruption pending retraction of the ironing means.

21. Apparatus of the character described, comprising a form on which a shirt may be dressed, wings having side edges generally parallel to the sides of the body of a shirt dressed on said form, said wings being movably mounted in said form and extensible from the sides thereof to fit snugly within shirts of varying sizes, chest means co-operating with both sides of said form and with said wings to press a shirt on said form, and said chest means being provided with recesses above said wings and opposite the shoulder portions of a shirt on said form, said recesses permitting the shirt-shoulder-supporting portions to extend thereinto whereby forms having shoulder portions of different width may cooperate satisfactorily with said chest means.

22. Apparatus of the character described, comprising a frame, cooperating opposed pressing members one of which is movably mounted upon said frame, a work holding form between said pressing members and movable with the movable pressing member, a source of drying air provided with an outlet, and conduit means on the form for discharging air upon the work and provided with an inlet coupled to said outlet by form movement.

23. Apparatus of the character described, comprising a frame, cooperating opposed pressing members one of which is movably mounted upon said frame, a work holding form between said pressing members and movable with the movable pressing member, a source of drying air provided with an outlet, conduit means on the form for discharging air upon the work, normally closed valve means controlling air flow from said outlet through said conduit means, and means operated by relative motion between said form and the frame for opening said valve means.

24. Apparatus of the character described, comprising a frame, cooperating opposed pressing members one of which is movably mounted upon said frame, a work holding form between said pressing members and movable with the movable pressing member, a source of drying air provided with an outlet, conduit means on the form for discharging air upon the work and provided with an inlet coupled to said outlet by form movement, conduit means on the movable pressing member for discharging a stream of drying air upon the work, and means arranged upon engagement of the movable pressing member with the form for establishing communication between the conduit means of the form and movable pressing member.

25. Apparatus of the character described, comprising a frame, movable ironing means supported by the frame at an ironing station, a rotatable turret carrying a plurality of movable work holding forms and adapted by its rotation to move them from a dressing station to the ironing station, turret operating means, means for applying the ironing means to the form, automatic control means for causing a cycle of operations of the turret rotating means and movable ironing means, including advance and recession of said ironing means, disabling means operable by and at the will of the operator for temporarily stopping operation of said control means, and means operated by said control means and effective upon operation of said disabling means for

delaying stop of said control means pending completion of the ironing operation.

26. Apparatus of the character described, comprising a frame, cooperating opposed pressing members mounted upon said frame and each movable toward and from the other, a work holding form movably mounted upon the frame between said operating members, operating means for advancing one pressing member toward the second thereof to a pressing position in which said operating means then serves as a backing preventing recession of the form, and operating means for then advancing the second pressing member toward the first thereof to apply ironing pressure to opposite faces of the form.

FORREST J. COUCH.
